CLAIM

I claim the ornamental design for dosage packaging for washing agents, as shown and described.

DESCRIPTION

FIG. 1 is a front perspective view of dosage packaging for washing agents embodying our new design;
FIG. 2 is a front side elevation view thereof;
FIG. 3 is a rear side elevation view thereof;
FIG. 4 is a right side elevation view thereof;
FIG. 5 is a left side elevation view thereof;
FIG. 6 is a top plan view thereof; and,
FIG. 7 is a bottom plan view thereof.
